(57) CLAIM

The ornamental design for a case cover, as shown and described.

DESCRIPTION

FIG. 1 is a right perspective view of a case cover according to an embodiment of the present invention.

FIG. 2 is a left perspective view of the case cover of FIG. 1.

FIG. 3 is a front view of the case cover of FIG. 1; and,

FIG. 4 is a top view of the case cover of FIG. 1.

The dashed lines illustrate environment that does not form a part of the present invention, and no claim is made to the material illustrated with dashed lines.

1 Claim, 4 Drawing Sheets
